UNITED STATES PATENT OFFICE.

BALDOMERO PASCHEN, OF CONCEPCION, CHILE.

PROPELLING DEVICE.

Application filed November 26, 1926. Serial No. 150,967.

The present invention relates to a mechanism for propelling boats and more particularly to means for actuating an outboard screw propeller. It is an object of the invention to provide a fluid actuated and manually operated motor for driving the propeller, the mechanism being operated by a motion simulating that employed to row with the ordinary type of oars. It is also an object of the invention to provide a steering device attached to the driving mechanism and removable therewith. Further objects will be apparent from the following description taken in connection with the accompanying drawings, in which:—

Fig. 1 illustrates the driving mechanism attached to the boat, portions of the machine being shown in section;

Fig. 1^a shows a part of the steering mechanism;

Fig. 2 represents a modification of the driving mechanism;

Fig. 2^a shows a clutch for connecting the driving piston to the driving shaft;

Fig. 2^b illustrates one method of attaching the steering mechanism to the boat;

Fig. 3 is a sectional view taken through the motor and Fig. 3^a a top view of the motor shown in Fig. 2;

Fig. 3^b is a plan view of a base member to which the motor is secured;

Fig. 4 is a sectional elevation of a form of the invention employing a plurality of levers for driving the motor;

Fig. 4^a is a sectional elevation, Fig. 4^c a sectional plan and Fig. 4^b an end view, partly in section, of means for attaching the motor to the boat;

Fig. 4^d shows one form of connecting rod for the levers;

Figs. 4^e and 4^f show a modification of the steering mechanism.

Referring to the drawings it will be seen that, in a cylindrical tube 1, is mounted a rotatable vertical shaft 2 on which is secured a plurality of spacing rings 3. A worm sleeve 4 fits on the shaft 2 being spaced therefrom by the rings 3. The lower end of the sleeve 4 is provided with an internal clutch face, preferably octagonal in shape and designed to engage a similarly shaped chamfered portion on the lower end of shaft 2. A coil spring 7 surrounds the lower end of the worm and cooperates with shoulders on the shaft 2 and

worm 4 normally to hold the octagonal portions of these members out of engagement, under which conditions the worm and shaft are rotatable with respect to each other. A piston 8 is slidably longitudinally of the tube 1 at the lower end of which is an air outlet 10 communicating with the atmosphere through the tube 9. To prevent rotation of the piston keys or other suitable guides 11 on the piston cooperate with longitudinal grooves provided in the tube. In this manner, upon reciprocation of the piston, the construction of which will be explained hereinafter, the worm is rotated and imparts its rotation to the propeller.

A curved tubular member 12 is secured to the upper end of tube 1 by means of a packed coupling 13 and a supporting member 14 clamped by means of a thumb screw 15 to the stern of the boat supports the tubes 1 and 12 in proper position, an adjustable collar 16 being provided for varying the height of the tube with respect to the water line. To an arm 17, which may be formed integral with the tube 12, is pivoted as at 25, a tiller arm 18. A flexible connection 19 provides communication between the interior of tube 1 and the pump cylinder 20, suitable air-tight couplings 21 clamping the connection to the tube and pump. A piston 20' is adapted to fit tightly in the cylinder and reciprocate therein, being operated by a lever 22 pivoted to the base 29 of the pump. This base is clamped to the bottom of the boat by a plurality of clamps 23. A seat 24 is so positioned with respect to the lever 22 that the pump may be operated much in the same manner as oars are manipulated.

The operation of this form of the invention will be apparent from Fig. 1 in which it will be seen that, there being an air-tight conduit between pistons 8 and 20', the reciprocation of piston 20' will produce a corresponding displacement of piston 8. The latter piston is constrained to move vertically but cannot rotate. Due to its cooperation with the worm 4 the latter is rotated when the piston 8 is reciprocated. The spring 16 is designed normally to support worm 4 and hold it out of engagement with chamfered end of shaft 2, but when the downward pressure of fluid acting on the piston 8 is sufficient to overcome this spring the worm and shaft engage to rotate the propeller.

peller. On the upward movement of the piston 8 the shaft and worm are disengaged, the shaft continuing to rotate in the same direction, a fly-wheel being provided for this purpose.

In Fig. 1^a is shown the manner in which the steering apparatus is operated. The tiller arm is provided with an aperture 28 to permit pivotal connection with the arm 17 (Fig. 1) and has a segmental portion 27 provided with teeth designed to mesh with teeth 26 on the tube 1. The lower end of tube 1 is rudder-shaped so that manipulation of the tiller 18 in the direction *a*—*b* will effect a change in course of the boat.

A modified form of the invention is illustrated in Figs. 2 and 2^a in which the tube 30 is provided with an interiorly threaded surface. The shaft 31 is square in cross section and, by means of bevel gearing, is adapted to rotate the propeller. The piston 32 is made in two parts, the lower part 33 being free to rotate with respect to shaft 31 and having threads or projections on its outer periphery designed to cooperate with the threaded interior surface of the shaft 31 to effect rotation of the piston. The upper portion 34 of the piston is provided with a square aperture so that it is constrained to rotate with shaft 31 but is free to move axially thereof. A spring 35 normally separates parts 33 and 34, but, as in the form of the invention shown in Fig. 1, pressure of the fluid from above overcomes the spring pressure and forces the parts into cooperative relation, serrated edges 34', 40 being provided to insure engagement of the parts. The part 34 has an elongated portion 47 adapted to extend through the part 33, a ring 36 being clamped to the end of the portion 47 to limit the relative axial movement between parts 33 and 34. Part 34 also has a tubular portion 39 adapted to hold spring 35 in position between the parts.

The pump in this form of the invention comprises an oscillating vane 42 pivoted within a casing 41, the latter having a cover plate 43 to permit access to the interior of the pump. A pinion 44 is secured to the vane 42 and cooperates with a toothed segment 45 forming part of the lever 22'. The pump is connected to the tube 30 by means of a flexible hose connection between the port 46 of the pump and the tubular member 57 at the upper end of tube 30. This member 57 is rotatably connected to tube 30, a packed union 54 and sleeve 50 insuring a fluid-tight joint, the packing 49, however, permitting relative rotation between these parts. In this form of the invention the handle 18' of the tiller is rotated, the bevel gear 51 on the shaft 52 being in mesh with a second bevel gear 53 secured to tube 30. The tiller shaft is designed to pass through the tube 57 and in order that the passage

may not be restricted the tube 57 is somewhat enlarged at the point where the tiller shaft passes therethrough as shown at 58 in Fig. 2^b.

The tiller and tube 30 are supported by a frame 60 and adjustable arm 61 clamped to the boat by a thumb-screw 62. The arm 61 is pivoted to frame 60 but a series of holes in the frame permits the elevation of lowering of the tube 30 and the propeller. A collar 63 on arm 61 is clamped on the tube 30.

It is obvious that more than one lever may be employed to operate the fluid motor, the modification illustrated in Fig. 4 employing three levers 22' connected together and adapted to be operated in unison by three persons seated on the seats 24' adjacent each lever. The levers are pivoted to a block 90 held to the bottom 83 of the boat by thumb-screws 74 and are connected by rods 75, 85 which, if desired, may be adjusted as to length as shown in Fig. 4^a. The motor 81 is mounted on a base 73 held to the boat bottom by screws 69 and having hooks 70 adapted to be engaged by one end of the frame of the motor. Thumb-screws 72 clamp the other end of frame to the boat, the bottom of the frame being serrated at 71 to prevent slipping. If desired, the motor may be provided with a handle 82 to facilitate its transportation.

The steering in this type of motor may be effected by foot levers 79, the tiller arm having a ring 76 to which cords 80 are connected. The cords 80 are also connected to the foot levers and pass over pulleys 78 held to the sides of the clips 77.

From the above description it will be seen that I have provided a portable outboard motor which depends solely on manual power, is positive in operation, its compactness and weight permitting it to be installed with minimum difficulty and in a limited space. While I have described several preferred embodiments of the invention, it is obvious that such changes as fall within the scope of the invention are permissible without departing from the spirit of the invention.

I claim:

1. A propeller apparatus of the class described comprising a boat, a propeller, a tubular member for supporting said propeller, said member being secured to said boat, a piston in said member, means for reciprocating said piston, a shaft within said member adapted to be rotated upon reciprocation of said piston, and means to operatively connect said shaft to said propeller when the piston is moved in one direction and disconnect the propeller from the shaft when said piston is moved in the opposite direction.

2. A propeller apparatus as claimed in claim 1, the means for rotating said piston

comprising a screw and means on the piston cooperating with said screw.

3. A propeller apparatus as claimed in claim 1, in combination with means for supporting said tubular member vertically and exteriorly of the boat, said means permitting rotation of the propeller about the axis of the tubular member.

4. A propeller apparatus as claimed in claim 1, in combination with a fly-wheel secured to said shaft for rotating the shaft

after the propeller and shaft have been disconnected.

5. A propeller apparatus as claimed in claim 1, the means for reciprocating said piston comprising a reciprocating fluid pump, and a conduit for maintaining constant communication between the pump and said tubular member.

In testimony whereof I hereunto affix my signature.

BALDOMERO PASCHEN.
